SWITCH STRUCTURE FOR LAMPS

Mark A. Beathan, Queens Village, N. Y.

Application May 20, 1947, Serial No. 749,321

7 Claims. (Cl. 240—123)

1

This invention relates to a switch-operating structure for lamps, and more particularly to an attachment adapted to be applied to a boudoir lamp or the like to enable the switch mechanism of the lamp to be operated with greater facility and convenience.

In many small table lamps, such as boudoir lamps, the lamp bulb is mounted in a vertically disposed socket, and a reciprocable switch bar is movably mounted in the socket below the bulb, this switch bar being moved in one direction to extinguish the lamp and in the other direction to light the lamp, the bar being adapted to remain in either position to which it is moved and offering resistance to movement from such position.

Lamps of this type are very often provided with a shade, and it is often inconvenient to operate the switch bar in that it is disposed below the shade where it is not readily accessible and also not visible.

It is contemplated by the present invention to provide a switch-operating attachment for such a lamp, the attachment being so constructed that it may be applied universally to practically all lamps of this type and so arranged that the switch bar referred to may be operated by push rods or push buttons accessible at the top of the shade where they not only may be conveniently operated but where they may be readily seen. Briefly, the device comprises a support consisting of two upright brackets, one upon each side of the lamp socket, and an integrally formed clamping means for securing the support to the lamp socket. In each of the bracket members is movably mounted a push rod which is suitably guided for movement in a vertical direction, or in a direction parallel to the axis of the lamp socket. These rods extend upwardly, and upon their upper ends are provided with adjustable push buttons whereby the height of the buttons may be regulated, so that they stand at approximately the upper level of the top of the shade, whereby they will be visible for operation, particularly in their upper positions, but, at the same time, will not protrude to a sufficient distance to be unsightly. Moreover, the supporting structure is so constructed that it may be manufactured economically, so that the entire attachment may be available at a relatively low cost.

One object of the present invention is to provide a switch-operating attachment for lamps, which will render the operation of the switch more convenient.

2

A further object of the invention is to provide an attachment readily applicable to boudoir lamps or the like employing a reciprocable switch bar, which attachment provides means for operating the switch bar from a point adjacent the upper end of the bulb or adjacent the upper portion of the shade if one is employed on the lamp.

A still further object of the invention is to provide a switch-operating attachment for lamps of the class described, which will render the operation of the lamp switch more convenient, and which, at the same time, may be economically manufactured, so that it may be made available at a relatively low cost.

To these and other ends the invention consists in the novel features and combinations of parts to be hereinafter described and claimed.

In the accompanying drawings:

20 Fig. 1 is a side elevational view of a lamp with my attachment applied thereto, the lamp shade being shown in section;

Fig. 2 is a sectional view on line 2—2 of Fig. 1, with the lamp bulb removed; and

25 Fig. 3 is a fragmentary enlarged side elevational view of the lamp socket, showing the manner of securing the attachment in place.

To illustrate a preferred embodiment of my invention, I have shown in Fig. 1 of the drawings a lamp of the boudoir type having a base or pedestal 10 to which is secured in upright position a socket 11. A lamp bulb 12 is disposed in the socket in the usual way, and a shade 13 of any usual form is shown in connection with the lamp, the shade in this instance being secured in place by clamping wires 14 which engage the bulb.

My attachment comprises a support consisting of a pair of bracket members 15 and 16, one disposed at each side of the socket 11. These bracket members may be made of sheet metal, and, as shown, extend generally in a vertical direction. Integrally formed with the members 15 and 16 is a clamp comprising an open band or ring 17, the adjacent free ends of the ring being turned outwardly, as shown at 18.

It will be understood that as is usual, the clamping ring 17 may be expanded to enable the ring to be slipped upon the socket and thereafter contracted, so that it may be caused to bind upon the socket in order to support the attachment in place. This function may readily be accomplished by a clamping member 19 having an elliptical opening 20 therein through which the outwardly turned ends 18 of the ring 17 extend. It

will be understood that, when the clamping member 19 stands in the dotted-line position, shown in Fig. 3, the ends 18 of the ring will stand in the direction of the lower axis of the elliptical opening 20 and permit the ring to expand, so that it may be slipped upon the socket 11. However, when the member 19 is turned into the plane of the ring or into the full-line position, shown in Fig. 3, the adjacent ends 18 will be brought together, and thus the ring will be clamped securely upon the socket.

As is usual in lamps of this kind, a switch bar 21 is reciprocably mounted in the socket 11, the switch bar being moved longitudinally in one direction or the other to close or open the switch to control the lamp. Upon the lower portion of each of the members 15 and 16 a lever 22 is pivoted at 23, each of these levers being provided with a depending portion 24 adapted to engage against one end of the switch bar 21, and each lever is also provided with a substantially horizontally disposed portion or arm 25 which extends at substantially right angles to the arm 24.

Adjacent the upper and lower ends of each of the supporting brackets 15 and 16, the metal of the brackets may be turned laterally or horizontally, as shown in the drawings, to provide guide lugs 27 and 28, each of these lugs having an opening 29 therein through which extends a push rod 30. The lower ends of these push rods engage the arms 25 of the levers 22, so as to operate these levers when the rods are pushed downwardly.

The upper ends of each of the rods 30 may be threaded as shown at 31, and adjustably secured on each rod is a push button 32 provided at its lower end with a nut 33 adapted to be threaded upon the portion 31 of the rods 30. If desired, a lock nut 34 may also be threaded upon the rods 30 in order to lock the push buttons 32 in adjusted position and prevent any tendency of these push buttons to be turned in the operation of the switch, and thus inadvertently move upwardly or downwardly when such adjustment is not desired. It will, of course, be understood that, if desired, the push buttons 32, which are hollow to receive the rods 30, may be interiorly threaded for adjustment upon these rods and the nut 33 omitted. In either event, they would be adjustable, so that the position of the upper ends of the push buttons 32 could be regulated, so that they stand at substantially the same height as the upper portion of the shade.

In the operation of the device, it may be assumed that the parts will stand in the position shown in Fig. 1 when the lamp is extinguished, and the left-hand button 32 is in a depressed position. The lower end of the rod 30 will engage the upper surface of the arm 25 of the corresponding bell crank lever 22 as will also the rod 30 on the right-hand side of the device. The parts will remain in this position due to the resistance of the switch bar 21 to movement, although it will be understood that, as the parts are of very light construction, there will be little tendency for the switch bar to be moved by the weight of the push rods. It will be seen that, in this position of the parts, the upper end of the right-hand push button 32 stands slightly above the top of the shade where it may be readily seen and engaged for operation. If it is desired to light the lamp, the right-hand push button 32 is pressed downwardly, which will cause the depending end 24 of the lever 22 to move inwardly toward the lamp and move the switch bar longitudinally of its axis, which will in the usual manner effect the

closing of the lamp switch. After this operation, the button 32 at the right-hand side of the lamp will stand in a depressed position, and the button 32 at the left-hand side of the lamp will then be in a raised position where it is readily accessible for operation as it will be necessary to operate this button to extinguish the lamp. If desired, the push buttons may be made of different colors, such as red and white, to indicate which one should be pressed to light the lamp.

As shown more especially in Fig. 2 of the drawings, the levers 22 may be provided with slotted portions 35 to receive the lower ends of the bracket members 15 and 16, so that a part of these levers will be disposed upon each side of the bracket, and the pivot pin 23 will extend through the bracket, so as to engage the levers on both sides thereof and thus effect a more balanced arrangement of the parts.

While I have shown and described a preferred embodiment of my invention, it will be understood that it is not to be limited to all of the details shown, but is capable of modification and variation within the spirit of the invention and within the scope of the claims.

What I claim is:

1. In combination with a lamp socket having a reciprocable horizontally movable switch bar, a support, means for attaching the support to the socket, a substantially vertically disposed push rod movably mounted in the support at each side of the socket, and means operably connecting each of said rods to the switch bar to actuate the latter in opposite directions by movement of the rods.

2. In combination with a lamp socket having a reciprocable horizontally movable switch bar, a bracket member disposed on each side of said socket, clamping means formed integrally with said members to attach them to the socket, a substantially vertically disposed push rod movably mounted on each of the bracket members, means transmitting motion from said rods to the switch bar, and guide lugs formed integrally with the bracket members to guide said rods in their movements.

3. In combination with a lamp socket having a reciprocable horizontally movable switch bar, a support, means for attaching the support to the socket, a substantially vertically disposed push rod movably mounted in the support at each side of the socket, means operably connecting each of said rods to the switch bar to actuate the latter in opposite directions by movement of the rods, and a push button adjustably secured to the outer end of each of the push rods to actuate the latter.

4. In combination with a lamp socket having a reciprocable horizontally movable switch bar, a support, means for attaching the support to the socket, a substantially vertically disposed push rod movably mounted in the support at each side of the socket, and means operably connecting each of said rods to the switch bar to actuate the latter in opposite directions by movement of the rods, said means comprising a lever pivoted on said support and engaging the adjacent ends of said switch bar and push rod.

5. In combination with a lamp socket, the axis of which is disposed in a substantially vertical position, and having a reciprocable switch bar movable in a horizontal direction, an upright bracket disposed at each side of said socket, means for attaching the brackets to the socket, a push rod mounted for substantially vertical

movement upon each of said brackets, a lever pivoted upon each bracket adjacent the lower end of the push rods, said lever having one arm extending in a substantially vertical direction to engage one end of said switch bar, and a second arm extending in a substantially horizontal direction to lie below and be engaged by the lower end of the push rod.

6. In combination with a lamp socket, the axis of which is disposed in a substantially vertical position, and having a reciprocable switch bar movable in a horizontal direction, an upright bracket disposed at each side of said socket, means for attaching the brackets to the socket, a push rod mounted for substantially vertical movement upon each of said brackets, a lever pivoted upon each bracket adjacent the lower end of the push rods, said lever having one arm extending in a substantially vertical direction to engage one end of said switch bar, a second arm extending in a substantially horizontal direction to lie below and be engaged by the lower end of the push rod, and means integrally formed with said bracket members and extending horizontally therefrom for guiding the push rods in their vertical movements.

7. In combination with a lamp socket having a reciprocable horizontally movable switch bar,

a bracket member disposed on each side of said socket, clamping means formed integrally with said members to attach them to the socket, a substantially vertically disposed push rod movably mounted on each of the bracket members, means transmitting motion from said rods to the switch bar, said clamping means comprising an open ring embracing said socket, the adjacent ends of said ring being turned outwardly, and a clamping lever having an elliptical opening in which the outwardly turned ends of said ring are received.
